Mass., a voluntary association of Massachu-
sets

Application August 21, 1944, Serial No. 550,401

3 Claims. (Cl. 2-14)

1

This invention relates to goggles and more particularly to novel ventilation means for the eyecups of such goggles.

One of the principal objects of the invention is to provide goggles adapted particularly for use by welders, furnace workers or the like with ventilation means which will prevent dirt, dust, etc., as well as injurious light rays from reaching the eyes of the wearer.

Another object is to provide goggle eyecups of the type having openings formed in the temporal side walls of the eyecups and having a perforated screen thereover in combination with a baffle internally of said eyecups and having channel portions correlated with the inner walls of the eyecups so as to direct air from the perforated screen in the temporal sides of the eyecups inwardly of the goggle through openings formed in said inner baffle plates adjacent the nasal sides of the eyecups with the said inner baffle simultaneously functioning to prevent particles which might traverse the perforated screen from reaching the eyes of the wearer and also for shunting light which might pass through said perforated screen to the eyes.

Another object is to provide an inner baffle plate of the character described which will be supported in assembled relation with the eyecups by clamping the lenses in position in said eyecups.

Another object is to provide an inner baffle plate of the character described shaped to blend with the face engaging portion of the eyecups in such a manner as to remove any sharp edges which might have a tendency to cut into the flesh and injure the wearer.

Other objects and advantages will become apparent from the following description taken in connection with the accompanying drawings and it will be apparent that many changes may be made in the details of construction and arrangement of parts without departing from the spirit of the invention as expressed in the accompanying claims. I, therefore, do not wish to be limited to the exact details of construction and arrangement of parts shown and described as the preferred forms only have been given by way of illustration.

Referring to the drawings:

Fig. 1 is a front elevational view of the device embodying the invention;

Fig. 2 is a sectional view taken as on line 2-2 of Fig. 1 and looking in the direction indicated by the arrows;

Fig. 3 is a slightly enlarged sectional view taken 55 drical member shaped to extend substantially

2

as on line 3-3 of Fig. 2 and looking in the direction indicated by the arrows; and

Fig. 4 is a side elevational view of the inner baffle member.

5 The invention is directed particularly to the provision of ventilation means for goggles of the type adapted particularly for use by welders, foundry workers, furnace workers and the like who are continually subjected to flying particles 10 and to relatively intense heat and injurious light rays such as are encountered in acetylene or arc welding or in furnaces.

15 The invention is directed particularly to providing means for adequately ventilating the goggles so as to avoid discomfort to the wearer and simultaneously protect the eyes from flying particles and from injurious light rays.

20 Referring more particularly to the drawings wherein like characters of reference designate like parts throughout the several views, the device embodying the invention comprises a pair of eyecups 5 each having a face engaging edge portion 6 shaped to the general contour shape of the face about the eyes. The said eyecups 5 are 25 preferably formed of non-metallic heat resisting material and more particularly of material which will not readily conduct heat. The said eyecups are each provided with a forward threaded portion 7 to which a lens retaining ring 8 is threadedly connected as shown best in Fig. 2. The said lens retaining ring 8 is provided with an inwardly extending flange portion 9 adapted to overlie the lenses 10. The said eyecups, on the temporal sides thereof, have a side wall portion cut away 30 to form a relatively large opening 11 therein surrounded by a shouldered seat 12. The shouldered seat 12 is adapted to receive a cover plate 13 having a plurality of vent openings 14 therein. The cover plate 13 is curved substantially to the outer 35 contour shape of the eyecups and is secured thereto by rivets or the like 15. The said cover plate 13 is provided with an integral tongue portion 16 having a slot therein for receiving the headband 17.

40 45 The opening 11 extends throughout a relatively large area in the side of the eyecups to afford ample passage of air inwardly of the eyecups through the vent openings 14.

A baffle plate 18 is positioned internally of the 50 eyecups and is provided with a peripheral flange 19 adapted to overlie the forward lens retaining edge of the eyecups in between the lenses 10 and the inner flange 9 of the lens retaining ring 8. The baffle plate 18 is in the form of a cylind-

throughout the entire area of the inner walls of the eyecups and is provided with a rear edge portion 20 shaped substantially to the contour shape of the face engaging edge portion 6 of the eyecups. The said edge portion 20 is flared outwardly slightly, as shown best at the location 21 in Fig. 2, to intimately fit with the surfaces of the inner walls of the eyecups throughout the inner contour of said eyecups. The said inner baffle 18 is provided with spaced wall portions 22 which are bent inwardly to provide inner channel members 23 spaced from the inner adjacent walls of the eyecups so as to permit the passage of air inwardly of said channels as indicated diagrammatically by the arrows 24, Fig. 3. The said channel portions 23, adjacent the nasal ends thereof, are provided with relatively large vent opening 25 whereby the air entering the channels through the vent openings 14 may pass inwardly of the eyecups adjacent the nasal side thereof as indicated diagrammatically by the arrows 26. The inner baffle 18 is preferably divided on the nasal side thereof as illustrated at 27 and has its wall portions 28 on the opposed sides of the line of division in relatively intimate contact with the inner surface of the eyecups on the nasal side thereof whereby the flow of air beyond the inner ends of the channel portions 23 will be restricted. The nasal side of the inner baffle plate 18 is provided with an opening 29 through which an eyelet 30 is adapted to extend. The eyelet 30, as shown in Fig. 3, is adapted to receive one end of a flexible chain-like bridge member 31 which is extended therethrough and which is locked in place by a clamp member 32 pivoted to the inner wall of the eyecups as illustrated at 33.

The baffle plate 18 is provided with an imperforate portion 34 on the temporal side of the eyecups lying in the rear of the cover plate 13 shaped to extend in substantially parallel relation with the curve of the cover plate 13 and to fit relatively intimately with the inner walls of the eyecups adjacent the front and rear sides of the opening 11. The flexible chain-like bridge 31 is preferably covered by a tubular member of heat resisting material 35.

It is particularly pointed out that the outwardly flared portion 21 has its edge surface engaging the inner surface of the eyecups adjacent the face contacting edge 6 so as to cause the outer wall of said edge portion 21 to lie substantially flush with the adjacent surface of the edge portion 6 thereby removing any sharp edge which might engage and cut into the flesh of the face of the wearer.

The inner baffle 18 is so dimensioned as to fit intimately with the inner wall of the eyecups and may be so formed as to have an initial circumferential dimension slightly larger than the circumferential dimension of the interior of the eyecups and thereby depending upon the slotted portion 27 to permit the said baffle to be forced into intimate relation with the internal wall of the eyecups and to be held in said relation by the flange 19 clamping gripped between the lenses and the adjacent edge of the eyecups.

From the foregoing description it will be seen that simple, efficient and economical means have been provided for accomplishing all of the objects and advantages of the invention.

Having described my invention, I claim:

1. A device of the character described comprising an eyecup member having a face contacting edge portion, side walls extending forwardly of said edge portion and terminating in a

forward supporting edge, said eyecup member having a relatively wide wall portion on the temporal side thereof with a vent opening therein and having a relatively narrow wall portion on the nasal side thereof, a baffle shaped to extend and fit within said eyecup member, said baffle having a wall portion on the temporal side thereof lying substantially flush with the adjacent inner surface of said eyecup and being of a width less than the width of the vent opening with the ends thereof spaced from the respective sides of said opening and having wall portions on the nasal side thereof contiguous with the inner adjacent surface of the eyecup, channel means formed in said baffle to extend inwardly of the eyecup from adjacent the opposed sides of the wall portion on the temporal side of said baffle, said channel means embodying spaced side wall portions lying in contiguous relation with the respective adjacent inner surfaces of the eyecup and each having an intermediate portion bulging inwardly of the eyecup and spaced from said adjacent surfaces and terminating in a closed end communicating with the portion in contiguous relation with the nasal side of the eyecup, said channel means each having an opening therein adjacent the closed end thereof communicating with the interior of the eyecup.

2. A device of the character described comprising an eyecup member having a face contacting edge portion, side walls extending forwardly of said edge portion and terminating in a forward supporting edge, said eyecup member having a relatively wide wall portion on the temporal side thereof with a vent opening therein and having a relatively narrow wall portion on the nasal side thereof, a baffle shaped to extend and fit within said eyecup member, said baffle having a wall portion on the temporal side thereof lying substantially flush with the adjacent inner surface of said eyecup and being of a width less than the width of the vent opening with the ends thereof spaced from the respective sides of said opening and having wall portions on the nasal side thereof contiguous with the inner adjacent surface of the eyecup, channel means formed in said baffle to extend inwardly of the eyecup from adjacent the opposed sides of the wall portion on the temporal side of said baffle, said channel means embodying spaced side wall portions lying in contiguous relation with the respective adjacent inner surfaces of the eyecup and each having an intermediate portion bulging inwardly of the eyecup and spaced from said adjacent surfaces and terminating in a closed end communicating with the portion in contiguous relation with the nasal side of the eyecup, said channel means each having an opening therein adjacent the closed end thereof communicating with the interior of the eyecup, and one of said spaced walls of the channel means having a substantially normally disposed flange thereon shaped to overlie the front supporting edge of the eyecup.

3. A device of the character described comprising an eyecup member having a face contacting edge portion, side walls extending forwardly of said edge portion and terminating in a forward supporting edge, said eyecup member having a relatively wide wall portion on the temporal side thereof with a vent opening therein and having a relatively narrow wall portion on the nasal side thereof, a baffle shaped to extend and fit within said eyecup member, said baffle having a wall portion on the temporal side thereof lying substantially flush with the adjacent inner surface

of said eyecup and being of a width less than the width of the vent opening with the ends thereof spaced from the respective sides of said opening and having wall portions on the nasal side thereof contiguous with the inner adjacent surface of the eyecup, channel means formed in said baffle to extend inwardly of the eyecup from adjacent the opposed sides of the wall portion on the temporal side of said baffle, said channel means embodying spaced side portions lying in contiguous relation with the respective adjacent inner surfaces of the eyecup and each having an intermediate portion bulging inwardly of the eyecup and spaced from said adjacent surfaces and terminating in a closed end communicating with the portion in contiguous relation with the nasal side of the eyecup, said channel means each having an opening therein adjacent the closed end thereof communicating with the interior of the eyecup, one of said spaced walls of the channel means having a substantially normally disposed

flange thereon shaped to overlie the front supporting edge of the eyecup and the other of said spaced walls of said channel means having an outwardly flared lip shaped to substantially engage the inner portion of the face contacting edge of the eyecup.
